UNITED STATES PATENT OFFICE.

HERMANN SCHROEDER, OF BREESE, ILLINOIS.

PNEUMATIC COLLAR-PAD.

SPECIFICATION forming part of Letters Patent No. 541,015, dated June 11, 1895.

Application filed April 15, 1895. Serial No. 545,802. (No model.)

To all whom it may concern:

Be it known that I, HERMANN SCHROEDER, of the city of Breese, Clinton county, State of Illinois, have invented certain new and useful Improvements in Pneumatic Collar-Pads, of which the following is a full, clear, and exact description, reference being had to the accompanying drawings, forming a part hereof.

My invention relates to an improved pneumatic collar pad, and consists in the novel construction, combination and arrangement of parts, hereinafter described and claimed.

In the drawings, Figure I is a front elevation of my improved collar-pad. Fig. II is a sectional view on the line II II of Fig. I, and looking in the direction as indicated by the arrow in Fig. I. Fig. III is a horizontal vertical sectional view taken, approximately, on the indicated line III III of Fig. I.

Referring by numerals to the accompanying drawings, 1 indicates the body of my improved pad, the same being a section of rubber or analogous flexible material, said body being either square, oval or round in plan view when flattened out. Said body 1 is bent or molded into an inverted U-shape, in order that it may be easily fitted and adjusted upon an animal's back or neck.

Formed in the sides of the body 1 after it has been bent into the proper shape are a series of apertures 2, for the purpose of ventilation to the space beneath the pad when it is properly located upon an animal.

Formed integral with the under side of the body 1 adjacent each end thereof are inflatable tubular sacks or pads 3, the same extending to the lower edges of the body 1. The ends of said sacks are closed and a connecting-tube 4 extends from one of said sacks to the other at a point immediately beneath the apex or upper end of the section 1.

An air-valve 5 of any common construction is provided with a cap 6, and serves as a means

for inflating the pair of sacks 3, as said air-valve is located in the upper and forward end 45 of one of said sacks. When the end of an air-pump is applied to this valve and said air-pump is manipulated, air will be forced into the sack in which said valve is located, and from thence said air will travel through the 50 tube 4 and into the opposite sack 3. When said sacks are properly inflated, the air-pump is removed from the valve 5, the cap 6 placed upon said valve, and the pad is ready to be placed in position upon an animal's neck. 55

A pad of my improved construction is inexpensive, is constructed in a single piece and greatly relieves the pressure and wear upon an animal's neck.

I claim—

1. A pneumatic collar pad, constructed of a single piece of flexible material bent into inverted U-shape, and provided on its under side with a plurality of integral inflatable sacks or cushions. 65

2. A pneumatic collar pad, constructed of a single piece of flexible material of inverted U-shape, integral inflatable sacks or cushions located on the under side of said piece of flexible material, and a tube connecting said 70 inflatable sacks or cushions.

3. A pneumatic collar pad, constructed of a single piece of flexible material of inverted U-shape, the same having apertures formed in the sides, inflatable sacks or cushions formed integral with the under side of said piece of flexible material, a flexible tube connecting said inflatable sacks, and an air-valve located in one of said inflatable sacks. 75

In testimony whereof I affix my signature 80 in presence of two witnesses.

HERMANN SCHROEDER.

Witnesses:

MAUD GRIFFIN,
JOHN C. HIGDON.
